(57) **CLAIM**

The ornamental design for a fork lift fork, as shown and described.

DESCRIPTION

The file of this patent contains at least one drawing executed in color. Copies of this patent with color drawings will be provided by the Office upon request and payment of the necessary fee.

FIG. 1 is a right side view of a first embodiment of a fork lift fork showing the new design;

FIG. 2 is a top view of the first embodiment of the fork lift fork of FIG. 1;

FIG. 3 is a front view of the first embodiment of the fork lift fork of FIG. 1;

FIG. 4 is a rear view of the first embodiment of the fork lift fork of FIG. 1;

FIG. 5 is a bottom view of the first embodiment of the fork lift fork of FIG. 1;

FIG. 6 is a left side view of the first embodiment of the fork lift fork of FIG. 1;

FIG. 7 is an enlarged view of the first embodiment of the fork lift fork of FIG. 1 showing the detail portion of the fork lift fork indicated in FIG. 1;

FIG. 8 is a left side view of a second embodiment of a fork lift fork showing the new design;

FIG. 2 is also a top view of the second embodiment of the fork lift fork of FIG. 8;

FIG. 3 is also a front view of the second embodiment of the fork lift fork of FIG. 8;

FIG. 4 is also a rear view of the second embodiment of the fork lift fork of FIG. 8;

FIG. 5 is also a bottom view of the second embodiment of the fork lift fork of FIG. 8;

FIG. 9 is a right side view of the second embodiment of the fork lift fork of FIG. 8;

FIG. 10 is an enlarged view of the second embodiment of the fork lift fork showing the detail portion of the fork lift fork indicated in FIG. 8;

FIG. 1 is also a right side view of a third embodiment of a fork lift fork showing the new design;

FIG. 2 is also a top view of the third embodiment of the fork lift fork of FIG. 1;

FIG. 3 is also a front view of the third embodiment of the fork lift fork of FIG. 1;

(Continued)

Fig. 7

FIG. 4 is also a rear view of the third embodiment of the fork lift fork of FIG. 1;

FIG. 5 is also a bottom view of the third embodiment of the fork lift fork of FIG. 1;

FIG. 7 is also an enlarged view of the third embodiment of the fork lift fork of

FIG. 1 showing the detail portion of the fork lift fork indicated in FIG. 1;

FIG. 8 is also a left side view of the third embodiment of the fork lift fork of FIG. 1; and,

FIG. 10 is also an enlarged view of the third embodiment of the fork lift fork of FIG. 1 showing the detail portion of the fork lift fork indicated in FIG. 8.

The first embodiment discloses a forklift fork with a marking on the right side but no marking on the left side as shown in FIGS. 1 through 7. The second embodiment discloses a forklift fork with a marking on the left side but no marking on the right as shown in FIGS. 2 through 5 and 8 through 10. The third embodiment discloses a forklift fork with a marking on the right and left side as shown in FIGS. 1 through 5, 7, 8 and 10.

The broken lines in the figures illustrate unclaimed environment and form no part of the claimed design.
